WARREN C. WRIGHT AND ARTHUR B. COCHERELL, OF CHICAGO, ILLINOIS; SAID COCHERELL ASSIGNOR TO SAID WRIGHT.

VALVE DEVICE.

Application filed June 9, 1928. Serial No. 284,132.

This invention relates to valve devices and more particularly to flush valves for toilet fixtures.

One object of the invention is to incorporate a pressure reducing means in the valve device whereby the action of the device will be silent under all pressures and particularly reduce a high inlet pressure so that the discharge from the valve will not be violent or exceed that as required for the desired functioning of the toilet apparatus with which the valve is associated.

Another object of the invention is to provide a relief or auxiliary valve of the non-tilting type and employ in connection therewith an operating mechanism whereby such valve will not be unseated in the closing of the main valve should the operating mechanism be held in valve open position.

Another object of the invention is to have the actuating mechanism for the auxiliary valve operable through the guide of the main valve and thus reduce the height of the valve device by having said actuating mechanism closer to the main valve.

A further object of the invention is to provide the auxiliary valve on the main valve with a spring mounting in order to insure proper and quick closing of the auxiliary valve when released.

A further object of the invention is to so form the seat for the auxiliary valve on the main valve that the seat forming means provides a convenient guide for the spring of the pressure reducer which is associated with the main valve.

A further object of the invention is to incorporate the housing for the packing of the timing pin directly in the valve housing so that the packing assembly may be easily made at a reduced cost of manufacture and with a minimum number of parts.

A further object of the invention is to reciprocably mount the auxiliary valve on the main valve and to provide a pivotally mounted lever on the main valve for actuating the auxiliary valve through the valve actuating mechanism which is carried by the main housing of the device.

The invention consists further in the matters hereinafter described and claimed.

In the accompanying drawings—

Fig. 1 is a vertical sectional view through a valve device of our invention;

Fig. 2 is a side view of the guide to be hereinafter described;

Fig. 3 is a top plan view of the same; and

Fig. 4 illustrates the action of the depressible pin to be hereinafter described.

The valve device of our invention comprises a main housing 1 of cast brass or other suitable material. The housing 1 is provided with a passage for the flow of liquids therethrough and such passage includes a chamber 2 within the housing and inlet and outlet connections 3, 4 at the opposite ends of the passage with the inlet connection 3 in constant communication with said chamber. The latter is divided from the outlet connection 4 by an upright cylinder 5 having its lower end cast integral with the housing and opening into said outlet connection. Said cylinder extends upward through the chamber 2 and has its upper end forming a seat for the main valve 6 which controls the flow of liquids through the housing 1 from inlet 3 to outlet 4. The connections 3 and 4 may be threaded for attachment to the source of water supply and toilet fixture, respectively.

The main valve 6 is in the form of a piston valve fitting within a cylindric chamber 7 provided in the housing 1 above the chamber 2 and forming an upward continuation thereof. The piston valve 6 has a sliding fit in chamber 7 and divides the latter from chamber 2 in all positions of the valve, whether open or closed. The valve 6 has a sealing leather 8 which engages the inner wall of the chamber 7 to seal it from chamber 2 in all positions of the valve.

The head of the piston valve 6 is formed by a metal plate or disc 6^a, to the under side of which is secured a depending tubular guide 9 having longitudinally extending radial webs 10 which engage the inner surface of the cylinder 5 to guide the piston 6 in its opening and closing movements. The webs 10 are made long enough so as to hold the main valve 6 central in all positions of its movement and thus provide for a silent operating valve by preventing chattering or hammering.

The tubular guide 9 has screw-threaded connection at its upper end with the plate 6^a and the sealing leather 8 is arranged about the guide, as shown. A gasket 11 is arranged about the guide beneath the sealing leather

and is held in place by a metal cup-shaped retainer 12 so as to seat on the upper edge of the cylinder 5 when the main valve closes, and thus cut off the flow of liquids through the valve from inlet 3 to discharge 4. The spaces between the webs 10 on the guide 9 provide the discharge passages for the valve when the main valve is open.

The plate 6^a is provided with a centrally disposed, upwardly extending tubular portion 13 open at its upper end and there provided with a gasket 14 which provides a seat for a relief or auxiliary valve 15. The valve 15 has a stem 16 which extends downward through the tubular projection 13 and into the guide 9 through a bearing spider 17 at the upper end of the guide. The spider holds the valve 15 central and guides it in its opening and closing movements. By this form of structure a non-tilting relief valve may be employed.

To close the valve 15 and maintain it tight against its seat when closed, we provide a coiled spring 18 about the stem 16 between the spider 17 and an arm 19 to which the lower end of the stem is connected. Said arm 19 is one of the arms of a lever 20 which is fulcrumed at 21 on a lug 22 carried by the guide 9 at the upper end of a vertical slot 23 in the cylindric wall of said guide, as shown in Fig. 2. The spring 18 presses down on the arm 19 and thus closes the valve. The stem 16 is connected to the arm 19 in any desired manner, as for example by having an enlargement 24 on the lower end of the stem beneath the arm 19 and a reduced portion 25 of the stem extending through a suitable slot or opening in the arm.

A by-pass 26 is cored in a boss 1^a on the housing 1 on the intake side of the valve during the casting of the housing. Said by-pass is enlarged where it opens into the inlet connection 3 so as to allow for a free and uninterrupted flow of liquids into the passage. The wall 27 of the housing on the rear side of the by-pass 26 extends downward in the flow through the connection 3 so as to provide a baffle for directing liquids into the passage 26. A port or hole 28 is drilled through the wall 27 at the upper end of the passage 26 so as to provide a communication between said passage and the chamber 7 above the piston valve 6 and thus permit liquids to fill the chamber 7 from the intake side of the valve.

The upper surface of the piston valve 6 as exposed to the water pressure in the chamber 7 is greater in area than the under surface of the valve which is exposed to the water pressure in the chamber 2 when the valve is closed. The result is that, although the pressure in the chamber 7 will be the same as on the intake side of the valve, the valve 6 would be held closed against its seat 65 at the upper end of the cylinder 4 by

reason of the larger area being exposed to the pressure in the chamber 7.

Arranged in the chamber 7 above the piston valve 6 is a coiled spring 29 having its lower portion bearing against the plate 6^a 70 about the tubular projection 13. The upper end of the spring 29 bears against an adjusting nut 30 on a threaded stud 31 which extends into a recess 32 provided in a cap or cover 33 screwed on or otherwise removably 75 connected with the housing over the top of the chamber 7. The upper end of the stud 31 fits in a concave seat 32^a in the recess 32 to hold the stud from lateral displacement. The nut 30 fits in said recess 32 and is held 80 in adjusted position on the stud by a lock nut 34. The spring 29 has a tension less than the hydraulic pressure required to open the valve 6. The stud, nut, and recess assembly at the cover 33 and the tubular 85 projection 13 at the main valve 6 provide a guide and support for the opposite ends of the spring 29 and hold it in central position. The nut 30 is channeled or grooved on its under side to receive the adjacent end 90 of the spring and hold it from displacement with respect to the nut.

The spring assembly just described provides a pressure reducer within the housing 1 and enables the pressure at which the 95 liquids are discharged past the valve 6 to be reduced to the pressure desired and thereby prevent splashing and violent action when the valve device is used with a high pressure system. By adjusting the nut 30 the 100 tension of the spring 29 may be regulated so as to reduce the pressure at which the liquids are discharged from the device to the low pressure desired. Thus the valve may be set to discharge the least amount of 105 liquids at the lowest pressure desired and economically function without waste of liquids or waste of pressure.

When equipping tall buildings, such as employed for offices, hotels, apartments, and the like, the pressures at which the various valves are desired to operate may be set to accord with the pressure conditions existing at different levels and thus provide for economic operation of the valves and the 115 amount of liquids employed in the flushing operation. In order that the water for the system for an entire building may reach the uppermost floors, it is necessary to generate a considerable pressure in the system. This 120 pressure is considerably higher at the lower floors than at the upper floors, and as a result our improved flush valves can be economically used because the pressure reducers incorporated therein can be set to compensate for the increased pressures encountered at the lower floors. This enables the valve to operate silently, quickly, positively, and economically at the different pressures 125 encountered on the different floors without 130

violent or agitated discharges from any valve and without subjecting the valves to excessive wear or strain by reason of the higher pressures as encountered on the lower 5 floors.

The flow through port 28 is controlled by a timing pin in the form of a screw 35, which is mounted in the boss 1^a in alignment with the port 28. The head of the screw is 10 accessible from the exterior of the housing 1 for adjustment by being located in a chamber 36 formed in the boss. The chamber is closed by a removable cap 37 to protect the screw.

15 The screw 35 extends through a suitable packing 39 which is compressed between the inner end of the chamber 36 and the head of the screw, as shown in Fig. 1, so as to prevent leakage about the screw. The packing 20 is so made that it conforms to the shape of the inner end of the chamber to make a tight joint and is resilient enough to be compressed by the screw in all adjusted positions thereof. To compress the packing, the screw has 25 a pressure member 40 which may be formed integral with the screw or constitute a separate part in the form of a washer as shown. This construction provides a simple form of packing and avoids the expensive housing 30 and packing arrangements as heretofore employed.

For operating the auxiliary valve 15 to relieve the pressure in the chamber 7 so that the main valve 6 may be opened by pressure 35 on its under side, we provide a novel form of operating mechanism, as shown in Fig. 1. This comprises a longitudinally movable plunger 41 slidably mounted in a tubular guide 42 carried by a boss 43 cast integral 40 with the housing 1 and extending outward therefrom, as shown. A union 44 is screwed on the outer end of the boss 43 and clamps the guide member 42 thereto. An oscillating handle 45 is supported by the union 44 and a coiled spring 46 in the union 44 normally maintains the outer end of the plunger 41 against the inner end of the handle 45 so that the plunger will be moved inward by the handle in any direction that the handle 50 may be oscillated. A cup nut 47 is screwed on the inner end of the tubular guide 42 against a packing 48 for preventing water leaking out of the valve about the plunger 41.

55 At the inner end of the plunger 41 is a block 49 located in the slot 23 and carrying a depressible pin 50 normally projected above the block by a coiled spring 51 surrounding the pin in a recess provided in the block for the pin, as shown in Fig. 1. The lower end of the spring 51 seats against a nut 52 screwed into the lower end of the recess and through which nut the pin moves so as to be guided by the nut. The upper 60 end of the spring engages under a shoulder

or enlargement 53 on the pin so as to project the pin above the block so that the pin will strike against the lower end of the lever 20 when the handle 45 is moved to open the auxiliary valve 15. The block 49 is provided with an upstanding projection 54 on the side of the pin opposite the arm 20 so that the pin will be braced against any undue strains that may be encountered on moving the pin 50 against the lower end of the lever 20 to lift the valve 15.

On moving the pin 50 against the lever 20 to lift the valve 15, the pressure in the chamber 7 is relieved through the open valve 15 and the hollow guide 9 and the main valve 6 is thereupon raised by the pressure on its under side to open the discharge side of the device to the intake side 3. As the main valve 6 moves upward, the lever 20 is carried therewith out of contact with and above the pin 50, whereupon the lever 20 is free and the spring 18 closes the auxiliary valve 15 and swings the lever 20 back into its normal valve-closing position. The pin 50 comes into contact with the lever 20 far enough 90 above its lower end to insure holding the auxiliary valve 15 open for the greater portion of the upward movement of the main valve 6, due to the fact that the lever does not trip off the upper end of the pin until 95 just before the main valve 6 reaches the limit of its upward movement. This necessitates substantially the same discharge of liquids from the chamber 7 in each operation of the valve, and as a result a predetermined flush 100 is obtained at all times, because the period of time for the refill of the chamber 7 to automatically close the main valve 6 is always the same.

In the closing movement of the main 105 valve 6, the pin 50 will be in the path of downward movement of the lever 20 should the handle 45 be still held in valve-opening position. With the pin 50 depressible, the main valve may still close without unseating 110 the auxiliary valve 15 because the lever 20 as it is brought into contact with the upper end of the pin 50 will depress it and allow the main valve to close without unseating the auxiliary valve. (See Fig. 4.) When 115 the handle 45 is released, the spring 46 will move the plunger 41 outward and carry the pin 50 from under the lower end of the lever 20, whereupon the spring 51 will immediately project the pin 50 upward so as 120 to return it to its normal position for again opening the auxiliary valve upon the operation of the handle 45.

With this construction, it is apparent that the pin 50 will not interfere with or 125 prevent the closing of the main valve in any position of the pin 50 whether directly under the lever 20 or completely released therefrom.

The slot 23 in the cylindric guide 9 not 130

only permits the pin 50 to reach the lever arm 20, but also permits the lever to swing without interference by the guide 9. The slot 23 guides the block 49 and thus maintains the pin 50 in proper alignment with the lower end of the lever 20 by preventing turning of the block with respect to the plunger 41. The slot 23 also permits the pin 50 to operate through the cylindric guide 9 and thus enables the height of the valve device to be materially reduced by locating the parts closer to the main valve 6 than is possible when the parts are located beneath the lower end of the guide. This feature of reducing the height of the valve device is also made possible by having the actuating mechanism for the auxiliary valve 15 operable between the ends of the guide 9, which when disposed as in Fig. 1 is cored out on one side for the purpose.

The upper ends of the webs 10 of the guide 9 terminate in an annular shoulder 55 against which the inner central portion of the gasket 11 is clamped on screwing the guide into the plate 6^a. This maintains the gasket 11 tightly in the retainer 12 and prevents the gasket from warping or weaving through saturation, and thus insures a perfect seat for the main valve 6 in its closing movement.

Briefly, the valve device operates as follows. On operating the handle 45, the auxiliary valve 15 is raised, relieving the pressure in chamber 7 so that the pressure on the intake side of the valve will lift the main valve 6 off its seat and permit the flow to pass from intake 3 to discharge 4 through guide cylinder 5 between the same and the guide 9. As soon as the lower end of the lever 20 is lifted from the pin 50, the spring 18 will close the auxiliary valve 15, whereupon the pressure in chamber 7 is again built up through by-pass 26, and main valve 6 will be automatically closed. This returns the lever 20 to a position whereby it may again be opened by actuating the handle 45.

The valve device shown and described is simple in its construction, positive and quick in operation, and silent at all times, and permits a predetermined discharge of water under all pressures, regardless of whether the handle 45 is held open or closed after having started the valve, or whether the handle is quickly or slowly operated. The valve device is less subject to wear, due to freedom of movement of its parts and also to the fact that no diaphragms are employed to buckle or twist under hydraulic strains in the opening and closing of the valve.

With the height and size of the valve reduced, the amount of metal required in the structure is materially lessened, thereby lessening the cost of manufacture of the valve. By having the actuating mechanism

for the auxiliary valve operable through the cylindric guide 9, the position of the operating mechanism may be brought more or less in the plane of the intake connection 3, thereby avoiding an oversized and ungainly structure as when the intake connection and the handle operating structure are in widely separated planes.

The details of structure and arrangement of parts shown and described may be variously changed and modified without departing from the spirit and scope of our invention.

We claim as our invention:

1. A flush valve, comprising a housing, a main valve in the housing for controlling the flow of liquids therethrough and opened and closed by the pressure on the intake side of the valve, an auxiliary valve carried by the main valve for controlling the actuation of the main valve, means for opening the auxiliary valve for starting the operation of the main valve, and means acting on the main valve about the auxiliary valve in the opening movement of the main valve to reduce the pressure at which the liquids are discharged past the main valve.

2. A flush valve, comprising a housing, a main valve in the housing for controlling the flow of liquids therethrough and opened and closed by the pressure on the intake side of the valve, an auxiliary valve carried by the main valve for controlling the actuation of the main valve, means for opening the auxiliary valve for starting the operation of the main valve, and means acting on the main valve about the auxiliary valve in the opening movement of the main valve to reduce the pressure at which the liquids are discharged past the main valve, said means being adjustable for controlling the pressure at which the liquids are discharged.

3. A flush valve, comprising a housing, a main valve in the housing for controlling the flow of liquids therethrough and opened and closed by the pressure on the intake side of the valve, an auxiliary valve carried by the main valve for controlling the actuation of the main valve, means for opening the auxiliary valve for starting the operation of the main valve, a spring in the housing on one side of the main valve and disposed to engage the main valve about the auxiliary valve to reduce the pressure at which the liquids are discharged past the main valve, and means for adjusting the tension of the spring for controlling the pressure at which the liquids are discharged.

4. A flush valve, comprising a housing, a main valve in the housing for controlling the flow of liquids therethrough and opened and closed by the pressure on the intake side of the valve, an auxiliary valve carried by the main valve for controlling the actuation of the main valve, means for opening the aux.

- iliary valve for starting the operation of the main valve, a spring in the housing on one side of the main valve and disposed to engage the main valve about the auxiliary 5 valve to reduce the pressure at which the liquids are discharged past the main valve, means for adjusting the tension of the spring, and means carried by the main valve about the auxiliary valve and forming a 10 guide and a support for the spring.
5. A flush valve, comprising a housing, a main valve in the housing for controlling the flow of liquids therethrough and opened and closed by the pressure on the intake 15 side of the valve, an auxiliary valve carried by the main valve for controlling the actuation of the main valve, means for opening the auxiliary valve for starting the operation of the main valve, a spring in the housing 20 on one side of the main valve and disposed to engage the main valve about the auxiliary valve to reduce the pressure at which the liquids are discharged past the main valve, means for adjusting the tension 25 of the spring, and means providing guides and supports for the opposite ends of the spring, said means at one end of the spring being on the main valve about the auxiliary valve and at the other end of the spring 30 being on the portion of the housing opposed to the main valve.
6. A flush valve, comprising a housing, a main valve in the housing for controlling the flow of liquids therethrough and opened 35 and closed by the pressure on the intake side of the valve, an auxiliary valve carried by the main valve for controlling the actuation of the main valve, means for opening the auxiliary valve for starting the operation 40 of the main valve, a spring in the housing on one side of the main valve and disposed to engage the main valve about the auxiliary valve to reduce the pressure at which the liquids are discharged past the main valve, 45 a stud shorter than the spring and disposed in the outer portion thereof and seating against a portion of the housing opposed to the main valve, and a nut on said stud for adjusting the tension of the spring.
- 50 7. A valve device, comprising a housing, a main valve and an auxiliary valve for controlling the flow of liquids through the housing, means whereby the main valve will be opened and closed by the pressure 55 on the intake side of the device, a spring associated with the main valve for reducing the pressure at which the liquids are discharged past the same, said main valve having a tubular projection forming a guide 60 and support for the spring, said auxiliary valve being mounted in said projection.
8. A valve device, comprising a housing, a main valve and an auxiliary valve for controlling the flow of liquids through the 65 housing, means whereby the main valve will be opened and closed by the pressure on the intake side of the device, a spring associated with the main valve for reducing the pressure at which the liquids are discharged past the same, a stud, and a nut screwed thereon for regulating the tension of the spring, said stud seating in a recess in one portion of the housing and with the nut slidably guided in said recess.
9. A valve device, comprising a housing, 70 a main valve and an auxiliary valve for controlling the flow of liquids through the housing, means whereby the main valve will be opened and closed by the pressure on the intake side of the device, said means including a timing pin having a head located in a recess in the housing, and a packing compressed against the inner end of the recess and about the pin by the head of the same to prevent leakage about the pin.
10. In a valve device, a housing, a main valve and an auxiliary valve for controlling the flow of liquids through the housing, means whereby the main valve will be opened and closed by the pressure on the 75 intake side of the device, said means including a timing pin having its head located in an outwardly opening recess provided in the housing, a packing about the pin at the inner end of the recess and compressed 80 by the head of the pin, and a removable cap for closing the outer end of the recess.
11. In a valve device, a main valve, an auxiliary valve carried by the main valve, a pivoted lever carried by the main valve 85 for opening the auxiliary valve, means for swinging the lever to open the auxiliary valve, and means for closing the auxiliary valve when released.
12. In a valve device, a main valve, an auxiliary valve carried by the main valve, a pivoted lever carried by the main valve for opening the auxiliary valve, and means for swinging the lever to open the auxiliary valve, said means permitting the main valve 90 to close without unseating the auxiliary valve should the lever actuating means be held in valve opening position.
13. In a valve device, a main valve, an auxiliary valve carried by the main valve, a pivoted lever carried by the main valve for opening the auxiliary valve, and means for swinging the lever to open the auxiliary valve, said means including a depressible member to be moved into engagement with the lever to swing the same and to be depressed by the lever in the closing of the main valve should said member be held in 95 the path of movement of the lever.
14. In a valve device, a housing having 100 an intake and a discharge, a piston valve in said housing to control the flow of liquids therethrough, a cylinder dividing the intake from the discharge and providing a seat for said piston valve, a tubular 105

guide carried by the piston valve and having a sliding connection with said cylinder, an auxiliary valve carried by the piston valve, and actuating means for opening the auxiliary valve operable through said cylinder.

15. In a valve device, a housing having an intake and a discharge, a piston valve in said housing for controlling the flow of liquids therethrough, a cylinder dividing the intake from the discharge and providing a seat for the piston valve, a tubular guide carried by the piston valve and slidably fitted in said cylinder, an auxiliary valve carried by the piston valve, a pivoted lever carried by the guide for opening the auxiliary valve, and means operating through a slot in the guide to engage the lever for opening the auxiliary valve.

20. 16. In a valve device, a housing having an intake and a discharge, a piston valve in said housing for controlling the flow of liquids therethrough, a cylinder dividing the intake from the discharge and providing a seat for said piston valve, a tubular guide carried by said piston valve and having a sliding fit in said cylinder, an auxiliary valve carried by the piston valve, and actuating means for the auxiliary valve operable through a slot in said guide, said means including an actuating element positioned in said slot and held from turning thereby.

17. In a valve device, a housing having an intake and a discharge, a piston valve in said housing for controlling the flow of liquids therethrough, a cylinder dividing the intake from the discharge and forming a seat for the piston valve, a tubular guide carried by the piston valve and fitting in said cylinder, an auxiliary valve carried by the piston valve, and actuating means for the auxiliary valve operable through a slot in said guide, said actuating means including a depressible member operating through said slot and permitting the piston valve to close regardless of the position of the actuating means.

18. In a valve device, a housing having an intake and a discharge, a piston valve in said housing for controlling the flow of liquids therethrough, a cylinder dividing the intake from the discharge and forming a seat for the piston valve, a tubular guide carried by the piston and slidably fitting in said cylinder, an auxiliary valve carried by the piston valve, and actuating means for the auxiliary valve operable through the guide so that the actuating means may be positioned close to the piston valve.

19. In a valve device, a main valve, an auxiliary valve carried by the main valve for controlling the operation of the same, a pivoted lever carried by the main valve and engaging the auxiliary valve, and

means for swinging the lever to open the auxiliary valve, said means when opening the auxiliary valve remaining in engagement with the lever long enough to hold the auxiliary valve open for substantially the entire opening movement of the main valve.

20. A flush valve, comprising a housing, a main valve in the housing for controlling the flow of liquids therethrough and opened and closed by the pressure on the intake side of the valve, an auxiliary valve carried by the main valve for controlling the actuation of the main valve, a pivoted lever associated with said valves to open the auxiliary valve, means for swinging the lever to open the auxiliary valve, means for closing the auxiliary valve, and means associated with the main valve for reducing the pressure at which the liquids are discharged past the same.

21. A flush valve, comprising a housing, a main valve in the housing for controlling the flow of liquids therethrough and opened and closed by the pressure on the intake side of the valve, an auxiliary valve carried by the main valve for controlling the actuation of the main valve, a pivoted lever associated with said valves to open the auxiliary valve, means for swinging the lever to open the auxiliary valve, said means permitting the main valve to close without unseating the auxiliary valve should the actuating means be held in valve opening position, and a pressure reducer associated with the main valve for controlling the pressure at which the liquids are discharged past the main valve.

22. In a valve device, a main valve, an auxiliary valve carried by the main valve, a lever pivotally mounted on the main valve for opening the auxiliary valve, and means for swinging the lever to open the auxiliary valve.

23. In a valve device, a main valve, an auxiliary valve carried by the main valve, a pivoted lever carried by the main valve for opening the auxiliary valve, means for swinging the lever to open the auxiliary valve, and means permitting the main valve to close without unseating the auxiliary valve in any position of the lever actuating means.

24. In a valve device, a housing having an intake and a discharge, a main valve in said housing for controlling the flow of liquids therethrough, an auxiliary valve carried by said main valve for controlling the operation thereof, a cylinder dividing the intake from the discharge and forming a seat for the main valve, a tubular guide carried by the main valve and having a sliding connection with said cylinder, said guide having a slot, a lever for opening the auxiliary valve and pivotally carried by

said main valve in a manner to swing in said slot, and means for swinging said lever to open the auxiliary valve.

25. In a flush valve, a housing having intake and discharge openings, a main valve in the housing for controlling the flow of liquids therethrough, an auxiliary valve carried by the main valve for controlling the operation thereof, a cylinder dividing the 5 intake opening from the discharge opening and forming a seat for the main valve, a tubular guide carried by the main valve and having a sliding connection with said cylinder, and actuating means for opening the 10 auxiliary valve, said guide having a slot through which the actuating means may operate.

26. In a flush valve, a housing having intake and discharge openings, a main valve 20 in the housing for controlling the flow of liquids therethrough, an auxiliary valve carried by the main valve for controlling the operation thereof, a bell-crank lever carried by the main valve and having one arm 25 engaged with the auxiliary valve, a cylinder dividing the intake opening from the discharge opening and forming a seat for

the main valve, a tubular guide carried by the main valve and having a sliding fit in said cylinder, and actuating means mounted 30 on the housing to engage the other arm of the lever to open the auxiliary valve, said guide having a slot to accommodate the lever and its actuating means.

27. In a flush valve, a housing having inlet and discharge openings, a main valve in the housing for controlling the flow of liquids therethrough, a cylinder dividing the inlet opening from the discharge opening and forming a seat for the main valve, an 40 auxiliary valve carried by the main valve, a tubular guide carried by the main valve and having a sliding fit in said cylinder, actuating means for swinging the lever to open the auxiliary valve, said guide having 45 a slot in one side to accommodate said actuating means, and pressure reducer means in the housing and acting on the main valve to control the pressure at which the liquids are discharged past the same. 50

In testimony whereof we affix our signatures.
